MACHINE FOR WASHING SILVERWARE

Jerome J. Foley, Rockville Centre, N. Y., assignor
to The Foley-Irish Corporation, a corporation
of New York

Application February 16, 1937, Serial No. 125,950

4 Claims. (Cl. 141—1)

This invention relates to new and useful improvements in washing machines and more particularly it pertains to machines for washing silverware such as used in restaurants and the like, and the machine illustrated herein is an improvement over that of my co-pending application, Serial Number 7,345, filed February 20, 1935.

One object of the invention is to improve the construction and mode of operation of washing machines and to provide such machines with mechanisms which will effect a better washing operation than prior machines.

A feature of the present invention resides in the provision of a new and novel construction of drum or container for the articles being washed.

A further feature of the invention resides in the provision of new and novel constructions whereby, after the washing operation has been completed, the drum or container in which the articles are carried may be bodily removed from the machine to facilitate the removal of the washed articles therefrom and the replacement thereof by other articles to be washed.

Other features of the invention relate to certain novel and improved constructions, arrangements, and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings,

Figure 1 is a perspective view of a machine constructed in accordance with the present invention,

Figure 2 is a perspective view on an enlarged scale illustrating the machine in open position with the drum in position to remove articles therefrom or to place articles therein,

Figure 3 is a vertical sectional view of the machine on a still further enlarged scale,

Figure 4 is a horizontal sectional view on a reduced scale, the view being taken substantially on the line 4—4 of Figure 3,

Figure 5 is a vertical sectional view on a reduced scale, the view being taken substantially on the line 5—5 of Figure 3,

Figure 6 is a fragmentary sectional view taken substantially on the line 6—6 of Figure 4,

Figure 7 is a fragmentary perspective view,

Figure 8 is a fragmentary view in elevation illustrating the construction of the perforated end walls of the drum,

Figure 9 is a detail sectional view taken substantially on the line 9—9 of Figure 8, and;

Figure 10 is a diagrammatic view illustrating the controls of the machine.

Referring to the drawings, the reference character A designates the frame of the machine. This frame comprises suitable leg members 20 10 having feet 21 and said legs are connected by braces 22. Carried in the lower portion of the frame there is a shelf or the like 23 and this, together with side walls 24 forms a compartment B which will be hereinafter referred to. In the upper portion of the frame there is a tank-like structure C comprising end walls 24 and 25, a bottom wall 26, and a hinged cover 27. As best shown in Figure 5, the cover 27 is hinged as at 28 to a rear wall 29 of the tank C.

The reference character D designates a drum, and this drum is mounted for rotation within the tank C. The drum has two end walls 30 and 31. The drum is circular in cross sectional form and that end which is closed by the end wall 30 is of 25 larger diameter than the end closed by the end wall 31. The side walls of the drum are provided with longitudinally extending inwardly disposed shoulders 32 extending substantially throughout the length of the drum, and these 30 shoulders serve to effect a tumbling of the articles within the barrel when the barrel is rotated.

The end walls 30 and 31 are perforated as at 34, and as best shown in Figure 9, these perforations 34 are tapered, the largest diameter thereof

being disposed outwardly of the drum. This construction provides a smooth inner face 35 for the end walls of the drum and by reason of the construction of the perforations, forks and similar articles having tines or other projections thereon do not become fixed to the end walls by reason of their tines being caught in the perforations as is the case where the end walls are of

relatively thin material, and the perforations of 40 equal diameter throughout the thickness of the material. The end walls 30 and 31 as well as the side walls of the drum are formed of relatively 45 thick material and the perforations are of such

size with relation to the thickness of the material employed as to prevent passage of the tines of a fork completely through the end walls, thereby

eliminating jamming and consequent damage to the drum in its rotation. The side wall of the drum closely adjacent the larger end thereof is 50 55

provided with a plurality of perforations 36 arranged in two circular series; these perforations not being formed in inwardly disposed shoulders 32 of the drum.

5 The end wall 30 of the drum may be secured in position by means of bolts screws or the like 37 which pass through openings 38 in the end wall 30.

10 The wall 31 which forms the closure for the opposite end of the drum is carried by a circular member 40 and is secured thereto by screws or the like 41. This circular member 40 I will hereinafter refer to as a driving ring since it provides the driving action for the drum D. This 15 ring has an open portion 41' in which is mounted a driving gear 42 the gear being secured to the driving ring by bolts screws or the like 43. The reference numeral 44 designates a shaft the inner end of which is positioned in the wall 31 as at 45 the outer end extending through a bearing member 47 which bridges the opening 48 in the end wall 25 of the tank C. This construction together with the stub shaft 49 upon the opposite end of the frame which rests in a cradle bearing 50 carried by the end wall 24 of the tank, provides the means for supporting the drum for rotation within the tank. The construction just described also provides means for readily removing the drum from the tank since its rear end, 30 or that end carrying the shaft 49 may be lifted, the shaft 49 clearing the cradle bearing 50 and permitting of the shaft 44 being withdrawn from the bearing member 47 to bodily lift the drum out of the tank.

35 The driving ring 40 is maintained in position upon the drum by means of the locking levers 52 (see Figure 3) which are pivotally mounted thereon and which have nose portions which engage beneath the heads 55 of bolts 56 (see Figure 3) carried by the drum. When the driving ring 40 is placed in position upon the end of the drum, the bolts 56 pass through openings in the driving ring after which the levers 52 are moved about their pivotal point until their nose portion 45 54 engages beneath the heads of the bolts 56, which operation locks the driving ring 40 in position upon the end of the drum. The driving ring provides for access to the interior of the drum and when removed leaves the drum open to receive 50 the articles to be washed, and when affixed to the drum, positions the end wall 31 to operative position in the drum.

55 Mounted in the end wall 25 of the tank there is a shaft 60. On the inner end of this shaft 60 there is a gear 61 which meshes with the gear 42 carried by the driving ring 40. Upon the outer end of the shaft 60 there is a sprocket wheel 62 and passing around this sprocket wheel 62 there is a driving chain 63, see Figure 3, which chain 60 also passes around a sprocket carried by the shaft 64. This shaft 64 is the driven shaft of a speed reducing gearing, not illustrated, but mounted within the housing 65 shown in dotted lines in Figure 3. This speed reducing gearing is driven by 65 a motor 66, the shaft 67 of which constitutes the driving element per se of the speed reducing gearing.

70 From the foregoing it will be apparent that when electric current is supplied to the motor 66, through the medium of the shaft 67, speed reducing gearing 65, shaft 64, driving chain 63, sprocket wheel 62, shaft 60 and gears 61 and 42, the driving ring 40 will be driven to rotate the drum in its bearings within the tank.

75 Means is provided for supplying a cleaning fluid,

preferably water, to the interior of the tank, and this means comprises a water supply line 70 controlled by a suitable valve 71 which when open, permits of filling to the desired level the tank with the cleaning fluid. Means is provided for also supplying the tank with a cleansing agent and this means comprises a tank 72 containing water or other fluid within which there is a supplemental tank 73. This supplemental tank 73 is either perforated or formed from screen and carries a cleansing agent 74, see Figure 5. The reference numeral 76 designates a pump which is hand operated by the plunger 77, and leading from the pump to an injecting nozzle 78, see Figure 3, there is a pipe or the like 79, see Figure 6. When the pump is operated, the cleansing agent in the tank 72 will be forced through the pipe 79 and discharged from the nozzle 78 directly into the tank.

80 A suitable drain in the form of a pipe 80 is adapted to carry off the water or cleaning fluid after a cleaning operation has been completed, and the discharge through this pipe 80 is controlled by a valve 81 which in turn is operated by a valve handle 82, see Figure 2. The reference 85 numeral 83 designates an overflow, and this overflow is in the form of a pipe 83 leading from the tank at a level above the bottom thereof and connected by a suitable fitting 85 to the drain 80 at a point below the valve 81. By this construction 90 and arrangement, should the level of the cleaning fluid rise above the lowest portion of the overflow, the fluid will be conveyed through the overflow pipe to the drain, thus preventing the level 95 of cleaning fluid rising to an undesirable level 100 within the tank.

105 Means is provided for supplying air for drying the articles after a washing operation, and this means comprises a conduit 90 within the lower end of which there is mounted an air impeller 91 driven by a motor 92. Mounted within this air conduit 90 there is a heater for heating the air, and this heater is designated by the reference character 94. When the motor 92 is driven, the heater 94 is supplied with electric current and the air passing in the presence thereof is heated to a degree which will effect a drying of the articles carried within the drum D. The upper end of the conduit 90 registers with the opening 48 in the end wall 25 of the tank, and closing this opening there is a plurality of hinged shutters 97. These hinged shutters are moved to open position by the passage of air through the conduit 90 and when the air supply is cut off they fall under the influence of gravity to the closed position in which they are shown in Figure 3, thus to prevent splashing of cleaning fluid from the interior of the tank into the air conduit 90 during the washing operation.

110 The reference numeral 100 designates a control box in which the control switches for operation of the motors and the controls of the various electrical devices are contained.

115 This control box includes a time switch which, after it has set, will maintain certain circuit conditions for a pre-determined time for which the switch is set. The time switch being of conventional type is not herein illustrated in detail.

120 In Figure 10 is shown the diagram or electrical system between the control switches and the various elements of the electrical apparatus, and this Figure 10 will now be described. The reference numeral 105 designates the main power line and this power line has one branch 106 connected as at 107 to conductors 108 and 109. The

conductor 108 is connected to a switch terminal 110 and the conductor 109 is connected to a switch terminal 111. The branch 112 of the source of supply is connected as at 113 to an armature 114 of an electro magnet 115 and this armature 114 is adapted under operating conditions to engage the switch terminal 111 when the electro magnet 115 is energized. As shown in said figure, the motor 66 which drives the drum 10 is mounted in this branch 112 of the main supply circuit. Leading off from the branch 112 as at 116, there is a conductor 118, and this conductor includes the motor 92 which drives the fan or air impeller 91. Also, this conductor 118 includes the electric heater 94 and from the electric heater 94 a conductor 120 leads to the point 121 where it is electrically connected to the armature 122 of an electro magnet 123. When this electro magnet 123 is energized the armature 122 will be moved to position where it will engage the terminal 110.

The reference numeral 130 designates a transformer and leading therefrom there is a conductor 131. The conductor 131 includes the winding 25 of the electro magnet 115 and also the winding of an electro magnet 140 from whence it continues to the point 141 where it is electrically connected to the armature 142 of the electro magnet 140. Leading from the conductor 141 at 30 the point 143, there is a conductor 144 which includes the winding of the electro magnet 123, and this conductor leads into a time switch of conventional construction within the control box 100. Leading from the conductor 131 from the point 35 147 there is a conductor 148, the end of which is open. Leading from the point 149 there is a conductor 150, and this conductor 150 is connected to the conductor 151 as at 152. The conductor 151 has an open point 153 and is connected as at 154 to the time switch. Leading from the transformer there is a conductor 157 which has an open point 158, and leading from the conductor 150 there is a conductor 160 which has an open point 161. Adapted to bridge the 40 open point of the conductor 148 and the open point of the conductor 160 there is a manually operated switch 162, and adapted to bridge the points 153 and 158 of the conductors 151 and 157, respectively, there is a switch 163. The transformer 130 is connected to the two branches of the 45 main source of power by conductors 169 and 170.

In said diagram the circuit of the main power line is illustrated in heavy lines while the control circuits are illustrated in correspondingly lighter lines. The electro magnets 115 and 123 and their associated armatures and wiring are mounted within a housing 180 located in the compartment B, and the motors 66 and 92 are also mounted within said compartment. The control box 100 50 which also includes the electro magnet 140 and its armature and the switches 162 and 163, is mounted upon the side of the machine, as best illustrated in Figure 2.

I will now describe the operation of the machine.

A lot of silverware to be washed is deposited in the barrel. This may be accomplished by removing the barrel as heretofore described, removing the driving ring therefrom, and placing the barrel in position on the machine in which it is shown in Figure 2. After the articles to be washed have been placed in the barrel, the driving ring is attached to the barrel in the heretofore described manner and the barrel positioned for operation within the tank, it being understood 55

that the cover will be closed. Water is next admitted by opening the valve 71 and when the proper level has been reached this valve is closed, cutting off the supply of water. Operation of the pump 76 will now provide a charge of cleaning compound or fluid into the cylinder and the machine is ready for starting. The machine is started by pressing the button 181 of the switch 162. This completes a circuit energizing the electro magnets 140 and 115. Energization of 10 the electro magnet 140 will attract the armature 142 thereof into engagement with the terminal 149 and complete a circuit through the switch 163 which, under normal conditions is closed to the transformer 130. Another circuit is completed through the winding of the electro magnet 140 and the winding of the electro magnet 115 and conductor 131 to the transformer 130. Energizing of the electro magnet 115 will attract 15 its armature 114 into engagement with the terminal 111 and will complete the circuit through the motor 66 by way of the conductor or branch 112, electric motor 66, armature 144, conductor 109, conductor 106. This set of the switch will cause operation of the motor 66 to rotate the 20 barrel through the driving mechanism thereof, which has been heretofore described. The washing operation continues until it is desired to discontinue the same, which is left to the discretion 25 of the operator. At the desired time the operator opens the valve 81 to permit of discharge of the washing fluid from the tank and after this has been completed the apparatus which supplies heated air to the drum for drying the 30 washed articles is set in operation. This is accomplished by operation of the handle 183 of the time switch which sets the mechanism of the time switch and also completes the circuit from the conductor 150 through the time switch, conductor 144, and the winding of the electro 35 magnet 123. This energizes this magnet and moves its armature 122 into engagement with the terminal 110. This completes the circuit through the motor 92 and the electric heater 94. With the parts in this position the drum is 40 rotated, the motor which drives the air impeller is in operation and the electric heater is energized as a result of which the drum will be rotated and heated air will be supplied to the drum in the heretofore described manner. The time switch 45 maintains this operation for a pre-determined length of time after which it trips and opens the switch 163, breaking all electric circuits and bringing both motors to rest and de-energizing the electric heater 94. The switch 163 has a button 50 55 182, and it is obvious from the foregoing that operation of this button may be employed to at any time stop the machine during operation thereof.

The foregoing operation having been completed the washed articles are removed from the 60 drum and the operation as described may be repeated.

While the invention has been herein described in its preferred form it is to be understood that it is not limited to the specific construction herein shown and that it may be practiced in other forms without departing from the spirit and scope thereof.

Having thus described the invention, what is claimed as new, is:

1. A drum for washing machines of the type described, said drum being of substantially cylindrical form, a perforated wall closing one end of the drum, a driving ring removably carried by the opposite end of the drum, and a perforated 75

- wall removably carried by the said driving ring and closing the adjacent end of said drum.
2. A drum for washing machines of the type described, said drum having end walls of relatively thick material, and a plurality of closely grouped openings extending through the end walls of the drum, said openings being of decided smaller diameter at their inner ends than at their outer ends whereby to provide a smooth inner 10 face for each end of the drum.
3. A drum for washing machines of the type described, said drum having end walls of relatively thick material, and a plurality of passages extending through said end walls, each of said
- passages tapering outwardly of the wall from a relatively small opening at its inner end to a relatively larger opening at its outer end to provide a smooth inner end for each face of the drum.
4. A drum for washing machines of the type described, said drum having end walls of relatively thick material and a plurality of passages extending through each of the end walls of the drum, said passages being of a length equal to 10 the thickness of the material of the end walls and being of larger diameter at their outer ends than at their inner ends.

JEROME J. FOLEY.
